FIG. 10.

FIG. 1 is a perspective view of a planter embodying my new design;

FIG. 2 is a rear elevation thereof;

FIG. 3 is an end elevation thereof;

FIG. 4 is a perspective view of a modified form of the planter shown in FIG. 1;

FIG. 5 is a rear elevation of the planter shown in FIG. 4;

FIG. 6 is an end elevation of the planter shown in FIG. 4;

FIG. 7 is a perspective view of another modified form of the planter shown in FIG. 1;

FIG. 8 is a rear elevation of the planter shown in FIG. 7;

FIG. 9 is an end elevation of the planter shown in FIG. 7;

FIG. 10 is a perspective view of another modified form of the planter shown in FIG. 1;

FIG. 11 is a rear elevation of the planter shown in FIG. 10;

FIG. 12 is an end elevation of the planter shown in FIG. 10; and

FIG. 13 is a plan view of the planters shown in FIGS. 1, 4, 7, and 10.

This application is a continuation application of my copending application Serial No. D. 74,254, filed April 1, 1963, and Serial No. D. 74,247, filed April 1, 1963, and now abandoned.

I claim:

The ornamental design for a planter, as shown and described.
